UNITED STATES PATENT OFFICE

2,523,886

SHOE BOTTOM FILLING MACHINE

Errol M. Thompson, Brockton, and Errol M. Thompson, Jr., Natick, Mass.

Application April 13, 1950, Serial No. 155,698

19 Claims. (Cl. 12—79.6)

1

This invention relates to shoe bottom filling machines, and pertains more particularly to improvements in automatic apparatus for ejecting from a well or chamber containing suitable plastic bottom filling material, a preformed filler biscuit, depositing the biscuit in the bottom cavity of a lasted shoe, and compressing the biscuit to fill the shoe bottom cavity.

The principal purpose of the invention is to provide an efficient and relatively economical machine of this type which will automatically perform the successive operations in a single cycle and which will complete the bottom filling procedure satisfactorily and rapidly, with minimum personal care or attention, once the cycle has been started by an operator of the machine.

More specifically, it is an object of this invention to provide manually adjustable means for varying the thickness of the ejected biscuit, while maintaining constant the outline or periphery of the biscuit, whereby the machine may be used to eject biscuits of predetermined volume capable of correctly filling shoe bottom cavities of variable depths and contours, as well as variable lengths or sizes, as regulated by the preset adjustment of the machine.

Another object is to provide a movable support for the forepart of the lasted shoe, and means timed to the operative cycle of the machine for elevating the supported shoe to biscuit receiving position, and finally to biscuit compressing position, while the shoe is held by the operator in proper position on the movable support.

A further object is to provide a bottom filling machine having a well or chamber for receiving a quantity of the plastic filling material; compressor members disposed in the filler chamber, at least one of said members being movable, for compressing and, preferably, partially shaping a portion of the filler to biscuit form; and a vertically reciprocable ejector-knife adjustably supported in said well, whereby its vertical position with respect to a delivery outlet in the bottom of the chamber may be regulated to eject a filler biscuit of predetermined volume through said outlet. Thus, the thickness of a biscuit compressed between the compressor members and beneath the ejector-knife, and ejected through said delivery opening by depressing the knife, may be regulated as aforesaid by setting the knife-adjusting mechanism at the proper position, prior to the operation of the machine.

Another object is to equip the bottom of the filler chamber with a slideable cover plate or gate valve having a discharge orifice or port movable into substantial registration with said delivery outlet at the proper phase of the machine cycle,

2

in time with the movement of the movable compressor member and the reciprocating ejector-knife, so that the ejected biscuit of compressed filler may be deposited in the shoe cavity as soon as the outline of the biscuit has been finally formed by forcing it through the outlet of the chamber bottom.

It is also an object of the invention to provide an outlet plate removably and replaceably inserted in the well bottom and having an outlet opening therethrough, so that said apertured plate defines the contour of the formed filler biscuit ejected therethrough, and also constitutes a pressure plate against which the shoe bottom may be pressed to receive the deposited biscuit. Pressure plates having openings of different sizes may thus be used interchangeably, if desired, corresponding valve plates and knife sizes being substituted when the pressure plate is changed.

Other features of the improved machine will be apparent from the following description of the preferred embodiments of the invention shown in the accompanying drawings, and will be pointed out in the appended claims. It will be understood, however, that the structural details of the apparatus herein illustrated and described may be modified to suit particular conditions or purposes, without departing from the essence of this invention as defined in said claims.

30 In the drawings,

Fig. 1 is a front elevation of one form of the improved machine, with parts broken away, showing the mechanism in the position of rest;

Fig. 2 is a plan view of the machine, partly broken away and omitting the hopper shown in Fig. 1 for delivering bottom filling material to the well or chamber of the machine;

Fig. 3 is an end view looking to the left of Fig. 1, showing a lasted shoe resting on the shoe support and against a toe guide;

Fig. 23 is an enlarged fragmentary view of the central portion of Fig. 22;

Fig. 24 is a view similar to Fig. 12, showing the position of the parts in the final stage of the cycle;

Fig. 25 is an enlarged fragmentary view of the central portion of the apparatus shown in Fig. 24, and also illustrating in section the forepart of the lasted shoe pressed against the delivery outlet of the chamber, with its bottom cavity filled with the compressed biscuit;

Fig. 26 is a view similar to Fig. 17, showing a modified form of the biscuit compressing and ejecting apparatus, certain parts being broken away, and other parts being shown partly in section; and

Fig. 27 is a detailed, fragmentary view of parts of the apparatus illustrated in Fig. 26, showing a different adjusted position of said parts.

In the recommended embodiment chosen for the purpose of illustration in Figs. 1 to 25, the shoe bottom filling machine is designed for use with a hot type of plastic, cork filling material of a relatively coarse and dry consistency (as contrasted with a wet, dense filler made of relatively fine particles) and is equipped with heating elements and thermal insulation, as hereinafter described. It will be understood, however, that the improved machine may be utilized with cold bottom fillers of the proper consistency, if desired, and that any suitably plastic types of bottom filling material, of the nature now commonly employed for this purpose, may be used for filling shoe bottoms in accordance with this invention.

The filler which applicants recommend for use in this machine is a hot, plastic, ground cork composition, with relatively large cork particles which is moldable under pressure and not excessively moist or fluid in consistency, such as the cork filler now commonly applied by hand to the bottoms of lasted shoes prepared for attachment of an outsole, according to the well known Goodyear welt process.

10 The insoles of such shoes are commonly formed with upstanding lips or flanges, providing sewing ribs to which the welt is conventionally stitched; and the space or cavity bordered by the sewing ribs or lips at the forepart of the shoe is desirably 15 occupied by a filler of plastic composition or sheet material, so that the outsole may be leveled against the shoe bottom. The volume of the space to be thus filled depends upon the height of the sewing ribs and the area bordered thereby 20 at the forepart of the lasted shoe, and the regulation of the thickness of the filler biscuit deposited in the bottom cavity by the improved machine is dependent upon these factors, rather than upon the length or "size" of the shoe.

25 As will be apparent hereinafter, each filler biscuit deposited by the improved machine may have the same peripheral contour, but may vary in thickness according to the adjustment of the extent of upward movement of the vertically reciprocated ejector-knife. The outlet opening defining the contour of the biscuit is preferably slightly smaller than the periphery of the bottom cavity of the smallest shoe which is to be bottom filled by the machine, which first deposits the pre-formed biscuit and then compresses and spreads the deposited biscuit so that it substantially fills the cavity to the height of the sewing ribs or lips on the insole. If desired, however, the size or contour of the outlet, may be varied by interchanging the removable apertured pressure plate, the valve plate and the ejector-knife, as aforesaid.

30 The invention will be disclosed herein by first describing the machine at rest, then explaining in greater detail the function of the machine, and finally setting forth the operation of the machine.

The machine at rest

As shown in Figs. 1 to 3 of the drawings, the improved machine comprises an upright frame 30 of steel or other suitable material, adapted to be mounted on the floor of a shoe factory; a bed or base plate 32 suitably fixed on the top of the frame 30 and extending beyond the ends of the frame, the projecting ends at least of the base plate, being of heavy metal to support operative mechanism mounted thereon or carried thereby; a shelf 34 pivoted at 36 in brackets 38 attached to the underside of one projecting end of the base plate, the opposite end of the shelf being adjustably connected to the rear margin of the base plate by a coupling 40 (Fig. 3); an electric motor 42 mounted beneath the shelf 34 and operatively connected by a belt 44 to the pulley of a gear box 46 which is mounted on top of a rearward projection of the base plate and which drives a cam shaft 48 extending transversely of the base plate and journaled in bearings 50 and 52 on said plate; rotation of the cam shaft being controlled by clutch mechanism 268; another supporting shelf 54 carried by the opposite end of the base plate and mounting a cam shaft 56 in journals 58 and 60, respectively, parallel to the shaft 48; a sprocket chain 62 operatively connecting sprockets on the respective shafts; and apparatus mounted on 65 the central portion of the base plate and compris-

ing a casing and associated mechanism for receiving plastic filling material, forming a biscuit therefrom, and ejecting the biscuit through an outlet in the base plate, in a timed cycle, as a result of the operation of the cams carried by the shafts 48 and 56 as hereinafter explained.

The central portion of the base plate is cut away to provide a rabbeted opening at 64 (Fig. 1) for the reception of a removable pressure plate 66 which is slideable transversely into said opening and guided by the rabbeted edges of the base plate at the sides of said opening or slot. The plate 66 has an opening 68 therethrough of a contour defining the shape of the filler biscuit to be ejected from the machine and deposited on the shoe bottom, and the bottom of said plate is preferably concaved at 70 around the periphery of said outlet opening 68 as best shown in Fig. 18. A toe stop or guide 72 is attached to the bottom of the pressure plate 66, rearwardly of the outlet opening 68. Several such plates, with openings of varying size or contour, may be provided for selective use in the machine, when desired.

A shoe support comprising a resilient cushion member 74 in a holder 76 is disposed beneath the outlet opening 68, the holder 76 being mounted on a rod 78 which is vertically slideable in suitable bearings of brackets 80 and 82 carried by the frame 30. The rod 78 is normally urged downwardly by a spring 84 connected to the frame near its bottom, and is moved upwardly against the resistance of the spring 84 by a Pitman arm 86, pivoted to a bracket at 88. One end of the arm 86 is pivotally connected to the rod through a slideable coupling 90 to the rod 78, and an opposite extension 92 of the arm or lever is actuated by a cam or shaft 48 as hereinafter described. A coil compression spring 94 surrounds the rod 78 between the coupling 90 and a fixed nut 96, so that upward movement of the rod is effected through the spring 94 which compresses to afford resilient pressure when the shoe support or rest 74 presses the lasted shoe against the bottom of the pressure plate 66, as explained below.

The apparatus for receiving and compressing the plastic filler comprises a generally rectangular casing erected on the base plate 32 and having front and rear sides 98 and 100, respectively, bolted or otherwise secured to the plate 32, and top plates 102 and 104 fastened to the side plates at the opposite ends of the box-like compartment formed by said side plates (Figs. 12-14). Said side plates and the top plate 102 are preferably covered with thermal insulation 106, such as sheet cork material. A hopper 108 also covered with thermal insulation 110 is suitably mounted on said side plates, between the opposed ends of the top plates 102 and 104, for delivering hot plastic filling material to a chamber 112 (Fig. 12) in the central portion of the casing formed by said side plates. The bottom of the hopper has a flange 114 resting on the inner end of top plate 102, and the opposite side of the hopper delivery outlet is provided with a depending deflector plate 116 to prevent the compressed filler in the chamber 112 from being squeezed out of the top of the chamber to the right of the hopper as shown in Fig. 1.

The ends of the filler chamber 112 are defined, in part, by the inner faces of a pair of compressor members, such as the slideable blocks or pistons 118 and 120, respectively. As best shown in Figs. 12 to 13, the compressor block 118, at the left of the machine as illustrated is slideable between the side plates 98 and 100, on a dove-tailed guide 122 75 movable and replaceable ejector-knife 154.

mounted on the underside of the top plate 102. Said block has an outwardly communicating longitudinal opening 124, defined by the top, bottom, side and inner end walls thereof, and a bar 126 extends across said opening or recess near its inner end. The block 120, hereinafter called a forming block or piston, at the right of the machine as illustrated, also slides between the side plates 98 and 100 on a dove-tailed guide 128, fastened to the top plate 104; and this bar has a similar outwardly communicating recess 130 in which a cross bar 132 is fixed. The two compressor blocks are thus slideable toward and from each other within the casing formed by the bed plate 32, the side plates 98 and 100, and the respective top plates 102 and 104.

A separate bottom plate 134 is provided in the left hand portion of the casing, as illustrated, between the bed plate 32 and the block or piston 118, said bottom plate being fixed in stationary position by fastenings extending through the side plates 98 and 100, as indicated in Fig. 13. The inner end of the bottom plate 134 is curved at 136, to correspond with the curvature of one side of the outlet opening 68 in the underlying pressure plate 66; and said bottom plate is fixed in such position that its curved end 136, which constitutes a biscuit-forming member, registers with the left half of the contour of said opening 68, as shown in the drawings, particularly Fig. 18.

The compressor block 118 slides on top of the bottom plate 134.

A sliding cover plate or gate valve 138 is disposed between the base plate 32 and the bottom plate 134, at the left of the machine, and between the base plate and the sliding block 120 at the right of the machine, as illustrated. Said plate has a discharge port or orifice 140 therethrough, the size of said port being no smaller than that of the outlet opening 68, and preferably of the same contour. The shape of that opening is indicated in Fig. 19, and also by the shape of the filler biscuit illustrated in Fig. 5, which is ejected through the valve orifice 140 and the outlet opening 68. The sliding plate 138 has a fixed bottom bracket 142 which slides in a longitudinal slot 145 of the base plate 32 (Fig. 12). The outer end of the bracket 142 extends beyond the edge of said plate and carries a roller 144 and a hook 146 which constitute a part of the means for moving the valve plate 138 longitudinally of the casing of the machine, below the sliding blocks and across the bottom of the intermediate filler chamber 112. The port 140 is so disposed that it may be brought into registration with the outlet opening 68, or moved to one side thereof (to the left as shown in Figs. 12 and 17) so that the outlet is closed by the plate 138. The plate may be removed and replaced with a plate with a port of different size.

The inner end of the compressor block 120 has a curved face 148, corresponding in contour to the right half of the outlet opening 68 and of the opening 140 in the gate valve 138, so that said block constitutes, in part, a biscuit-forming element, in co-operation with the curved end or wall 136 of the bottom plate 134, when the block 120 is moved to its inwardmost position as shown in Figs. 16, 24 and 25. A dove-tailed upright guide member 150 is fastened to the central portion of the curved face 148 of the biscuit-forming block 120 (Fig. 16) and constitutes guiding means for the slide 152 which carries at its bottom a replaceable ejector-knife 154.

The ejector-knife has a peripheral contour corresponding in shape to the contour of the outlet opening 68, the knife being slightly smaller than said openings so that it may pass therethrough, when the openings are in registration, to eject a formed filler biscuit through the bottom of the chamber 112, when the ejector-knife is vertically reciprocated by moving the slide 152 on the dove-tailed guide 150. The forward edge and opposite sides of the knife are beveled at 156, to provide a cutting edge (Fig. 16). The top of the slide 152 has a coupling 158 for attachment of a lever 160, pivoted in a bracket 162 mounted on the block 120 and movable in a slot 164 of the top plate 104, whereby the slide 152 and the ejector-knife 154 are vertically reciprocated in the chamber 112 by movement of the pivoted lever 160.

The ejector-knife, its guide 152, and actuating lever 160 thus move longitudinally of the casing together with the block 120 when the latter is actuated. Said block has an outward extension 166 carrying a roller 168, engageable by a cam as hereinafter described.

Means are provided for regulating the extent of upward movement of the ejector-knife 154, during reciprocation of the guide 152, said means comprising a steel wedge member 170, slidable transversely of the machine on a platform 172 erected on posts 174 on the projecting end of the base plate at the right of the machine as illustrated. Movement of the wedge is guided by bottom bolts or studs 176 which ride in a slot 178 of said platform, and is actuated by a lever arm 180 connected to one of said bolts and to a crank 182 pivoted at 184 and having a handle 186. The handle preferably has an index member 188 movable across a curved flange 190 at the forward end 192 of the platform 172, whereby the sliding adjustment of the wedge 170 may be indicated by a number scale or the like on said flange. The numbers on the scale are intended to indicate to the operator the proper setting of the handle 186, according to the desired thickness of the filler biscuit to be formed in and ejected from the machine through the openings above described.

The outer end 194 of the pivoted lever 160 carries a roller 196 engageable with the inclined top surface of the wedge 170, when the slide 152 is in uppermost position, so that the upward limit of the position of the ejector-knife 154 is limited by the setting of the wedge 170.

Longitudinal movement of the compressor blocks, the sliding valve plate 138 and the shoe support lever 86—92 is actuated by cam members on the shafts 48 and 56, driven by the motor 42, as aforesaid. The cams on shaft 48 include a front cam 198 bearing against a roller 200 at the end of the lever arm 92, for elevating the shoe support 14; a middle cam 202 engageable with a roller 204 on the lever 160 which vertically reciprocates the ejector-knife, as aforesaid; and a rear cam 206 which engages the roller 168 carried by the outer extension of the biscuit-forming block 120. The roller 200 is held against the edge of cam 198 by action of the return spring 84 of the shoe support rod 78; the roller 168 is held against the edge of the cam 206 by a spring 208 attached at one end to the bar 132 in the socket of the block 120 and, at its other end, to a hook 210 at the right end of the base plate as shown in Fig. 1; and the roller 204 is held against the edge of the cam 202 by a spring 212, attached to the outward extension 194 of the lever 160, and to a stud 214 extending from the bracket 38, as shown

in Fig. 1, except when the roller 196 rests upon the wedge 170 as shown in Fig. 17.

The cams carried by the shaft 56 at the left of the illustrated machine include a front cam 216 which engages the roller 144 of the bracket 142 on the sliding gate valve 138; and a rear cam 218 which engages a roller 220 on a lever 222 having its lower end pivoted at 224 to a bracket 226 on the bottom of the shelf 54, the upper end of said lever being pivoted at 228 to a link 230 pivotally connected at 232 to an extension 234 of the compressor block 118. The roller 144 is held in engagement with the edge of cam 216 by a spring 236 connected at one end to the hook 146 on bracket 142 and at its opposite end to a stud 238 on an extension of the shelf 54; and the roller 220 is held in engagement with the edge of cam 218 by a spring 240 attached at one end to the cross bar 216 in the socket of block 118, and at its opposite end to a stud 242 on another extension 244 of the shelf or platform 54.

The several movable parts of the biscuit forming, ejecting and compressing mechanism are thus individually actuated by cams operating against the resistance of springs which normally urge said parts to inoperative position as shown in Fig. 1. The cams are so shaped as to control the movement of the several parts in timed sequence during the operative cycle of the machine, so that no other adjustment or control is necessary during the cycle.

The hot plastic filling material dumped into the chamber 112 through the hopper 110 is maintained at proper temperature within the insulating casing on the base plate 32 by heating elements such as the electric heating units 246 and 248 mounted on the bottom of said plate and suitably connected to a source of current. A thermostatic switch element 250 (Fig. 1) in the circuit of the motor 42 is preferably mounted on top of the casing and constitutes a control switch which prevents the operation of the motor when the temperature in the casing or chamber 112 is below the desired temperature of the filling material. As this switch forms no part of the present invention, its structural details and connections are unimportant.

Function of the machine

The improved machine operates to form and eject a filler biscuit 252 (Figs. 5 and 6) having a contour defined by the outlet opening 68 and a thickness regulated by the adjusted maximum height of the ejector-knife, and to deposit the ejected biscuit in the central portion of a bottom cavity 254 (Fig. 4) of a lasted shoe 256 having an insole 258 formed with the upstanding sewing ribs or lips 260 which define the cavity at the forepart of the shoe. After the biscuit is deposited, the shoe bottom is pressed more firmly against the concaved surface of the pressure plate 66, and further downward travel of the ejector-knife then compresses and spreads the biscuit 252 (Fig. 7) until it completely fills the forepart cavity, as shown at 262 (Figs. 8 to 10).

The biscuit of compressed filling material is partially formed between the forming faces 136 of the bottom plate 134 and 148 of the forming block 120, respectively, when the compressor blocks are moved toward each other to compress the filler in the bottom of the chamber 112 and squeeze it beneath the ejector-knife 154, the cutting edge 156 of which slices through the compressed filler to define the top of the biscuit. When the knife has moved to a position imme-

diately above the outlet opening 68, the port 140 of the gate valve 138 has been moved to a position in registration with said outlet 68, and the block 120 has come to rest. The knife then moves downwardly to eject the formed biscuit through said port and outlet opening and into the shoe bottom cavity 258, while the ribs 260 lightly engage the bottom of the pressure plate 66. At this moment, the cushion 74 of the shoe support is at the position indicated by the broken line 264 (Figs. 12 and 15). Further movement of the operative mechanism causes the foot support to be elevated to the position indicated by the broken line 266, thereby pressing the shoe bottom against the pressure plate, and further depresses the ejector-knife 154 to compress and spread the deposited biscuit, as aforesaid.

It will be understood that, prior to the operation of the machine, the forepart of the lasted shoe is placed on the support 74, with the toe of the shoe engaging the toe guide 72, while the shoe support is in the position indicated in full lines in Figs. 1, 12 and 15. The rear part of the shoe is grasped by the hand of the operator, to hold the forepart bottom in substantially horizontal position for proper engagement with the pressure plate when the shoe support is thereafter elevated.

Operation of the machine

To start the machine, the operator engages the motor clutch 268, which may be a standard pin-type clutch member, by pressing his foot upon the treadle 270 to actuate the clutch control rod 272 (Figs. 3 and 3A) which is suitably connected with the clutch mechanism. A return spring 274 connected to the pedal 270 and to the frame 30 normally holds the actuating rod 272 in inoperative position. Engagement of the clutch causes the drive shafts 48 and 56 to rotate at a uniform rate, thereby rotating the cam drives above described.

The successive phases of the cycle of operation are diagrammatically outlined in Fig. 11 starting with the machine at rest, as shown in Figs. 1 to 3 and 12. Successive stages, showing the relationship of the essential parts during the cycle of operation, are illustrated in Figs. 17, 20, 22 and 24.

In Fig. 12, the shoe support is in its lowermost position, to receive the lasted shoe inserted by the operator; the delivery outlet 68 is closed by a portion of the cover plate or gate valve 138 and by the partially depressed ejector-knife 154 which rests on top of said plate; and the respective compressor blocks rest at their most outward positions.

In Fig. 17, the foot rest has been moved upward to the position indicated at 264 (Figs. 12 and 15) to hold the shoe in filler receiving position; the outlet 68 is closed by the cover plate or valve; both compressor blocks have been moved to the right of the machine as illustrated; and the ejector-knife has also been moved to the right and as moved upward, dropping the end 194 of the lever 160 so that the roller 196 rests on the wedge 170. It will be understood that the wedge has previously been set to an adjusted position predetermining the thickness of the filler biscuit to be formed and deposited.

In Fig. 20, the shoe rest remains in its previous position; the outlet is still closed by the cover plate; the left compressor block 118 has moved to its extreme forward position; the right compressor block 120 has reversed its movement and

has moved slightly to the left; and the ejector-knife remains at the same vertical position, under control of the roller and wedge aforesaid. At this stage, the filling material has been compressed and forced under the knife into the space between the two biscuit forming faces mentioned above (Fig. 21), and the knife is cutting through the compressed material to form the top of the biscuit.

10 In Fig. 22, the position of the shoe rest has not changed; the cover plate or gate valve is moving to the right, to bring its orifice 140 over the delivery outlet 68; the biscuit forming block 120 has reached its inwardmost position; the other compressor block 118 is moving to the left; and the ejector-knife is disposed over the outlet opening, with its forward cutting edge substantially registering with the curved edge of the biscuit forming plate 134, thereby completing the formation of the biscuit 252 of compressed filler material. The biscuit is now ready to be ejected, as soon as the gate valve has fully opened.

In Fig. 24, the shoe support has been elevated to press the shoe bottom against the pressure plate 66, thereby slightly compressing the resilient pad 74 (Fig. 25); the valve plate 138 is in fully opened position; the position of the biscuit-forming block 120 has not changed; the compressor block 118 has moved to its extreme outward position, or position of rest; and the ejector-knife has been depressed by action of the cam 292 on the lever arm 60, to eject the formed biscuit (Fig. 24), deposit it in the shoe cavity and compress and spread the biscuit to fill the cavity as indicated at 262 in Fig. 25.

In the remaining phase of the cycle, the parts are restored to the position of Fig. 12; the clutch is disengaged by removing pressure on the treadle 270, and the lasted and filled shoe is removed by the operator, who may insert another shoe and then repeat the cycle of operation. It will be observed that the operation of the machine is completed in a single, automatic cycle, without attention on the part of the operator except to maintain pressure on the clutch treadle and hold the shoe against displacement from its proper position on the support 74 and in the toe guide 72. It will also be understood that there is no need for ironing the plastic filling material which has been compressed in the shoe bottom cavity, after the filled shoe has been removed from the machine.

The cycle of operation is completed very rapidly, normally within one and one-quarter seconds, so that the machine will fill the bottoms of a very large number of shoes during a day's working hours. Inasmuch as the actuation of the moving parts of the machine is performed solely by cam elements, the use of complicated gearing has been avoided.

Modifications in the machine

As previously explained, the compressor members 118 and 120 of the machine shown in Figs. 1 to 25 are both movable and are associated with the stationary forming plate 134 disposed at one side of the outlet in the well bottom; and the gate valve or plate 138 is independently slideable between the plate 134 and the base plate 32 of the machine. This machine works very satisfactorily when the filler material is sufficiently coarse and dry to feed down without clogging or balling up; but when the filler is relatively fine and wet and more plastic, so that it packs 70 in a dense mass under pressure, the efficiency

of the machine is somewhat impaired by clogging of the gummy material in the chamber 112. This clogging tendency would be obviated by eliminating the forming plate 134, fixing the forming block 129 in stationary position at the edge of the outlet opening 68 (as in Fig. 22), and sliding the compressor block 118 directly on the valve plate 138; but we prefer to use the modified machine shown in Figs. 26 and 27 when filling shoe bottoms with a relatively wet filler composition composed of finer cork particles which tend to pack together more solidly in a dense mass.

The modified machine is similar in construction, function and operation to the machine heretofore described in detail, except for the structural changes indicated in Figs. 26 and 27, and the elimination of certain parts as hereinafter explained. The bed plate of the modified machine is the same as the bed plate 32 of the machine of Figs. 1 to 25, and is so designated in Figs. 26 and 27. The pressure plate 66 is also the same as previously described, and is slidably fitted to the rabbeted opening of the bed plate in the same manner. The shoe pad 74 and holder 76 are also constructed and arranged as previously explained, beneath the delivery outlet 68 and near the toe guide 72. Cam shafts 348 and 356 of the modified machine, correspond in general arrangement and purpose to the cam shafts 48 and 56, respectively, of the previous machine. An adjustable wedge member 370 corresponds in construction, purpose and mode of actuation to the wedge member 170 heretofore described.

The pressure plate 66 has the outlet opening 68 conforming, as aforesaid, to the contour of the biscuit to be ejected from the machine and deposited in the shoe bottom as indicated in Fig. 25. A sliding valve plate 338 having the valve port 340, is arranged to slide over the base plate 32 and pressure plate 66, so that the port 340 may register with the outlet opening 68, in a manner similar to the operation of valve 138 of the first machine. Plate 338 is, however, attached directly, as by screws or other fastenings, to a sliding compressor block 318 (Fig. 26) which corresponds in purpose to, but differs in size and shape from the block 118 heretofore described.

Block 318 slides in a casing as aforesaid and over the bottom of the chamber 312 between the side walls of the chamber (the rear wall of the casing being indicated at 300) and beneath a guide block 322 which constitutes a part of one end of the chamber 312. The block 318 is actuated by a lever 330 pivotally connected by a link 332 to a bracket on said block, the arm 330 being hinged on a fixed pivot 336, and carrying a roller 338 engaging the cam 350 on the shaft 356. The block is normally retracted to the open position shown in full lines in Fig. 26 by a spring which acts in a manner similar to the spring 240 of the previous machine. Actuation of the cam 350 causes the block to be moved from the full line position of Fig. 26 to the broken line position thereof, and back, during one cycle of operation of the machine.

At the opposite end of the well 312, the block 320 is fixed in stationary position between the side walls of the chamber. The inner face 352 of said block is formed as a curved recess, so that excess filler material moved toward said face by movement of the block 318 will tend to be moved upwardly and backwardly into the well. The inner edge of the bottom of the block 320 may be shaped to conform to the contour of, and

register with, the outlet opening 68; but this curvature is not essential to the operation of the modified machine.

An ejector-knife 354, similar in form and purpose to the knife 154 of the previous machine, is arranged to be reciprocated toward and from the outlet 68 in the bottom of the well 312. In the modified machine, the knife is attached to a rod or plunger 360 slidable vertically in bearings 362 of a sleeve 364 attached to a plate 366 fixed between corresponding brackets 368 suitably mounted in upright position on the wall of the machine as indicated at 370. The upper end of rod 360 is pivotally connected at 372 to a rocker arm 374 hinged at 376 in the bracket 368 and pivotally connected at its opposite end 378 to a sleeve 380 slidably in an opening in the plate 366. The rod 360 may be hollow to receive an elongate heating unit (not shown) for heating the knife 354, if desired.

A rod 382 is adjustably mounted in the sleeve 380 and carries at its lower end a roller 384 engaging a cam 302 on the shaft 348. The cam 302 corresponds in purpose to the cam 202 of the previous machine. Hence, actuation of the cam 302 lifts the push rod 382 and its sleeve 380, thus rocking the arm 374 and depressing the rod or shaft 360 to move the ejector-knife 354 downwardly from the full line position to the broken line position of Fig. 26. In such movement, the knife passes through the port 340 in the valve plate 338 and through the outlet opening 68 in the pressure plate 66, thereby ejecting the compressed filler material through the outlet and into the bottom cavity of the lasted shoe supported upon the rest 74.

The extent of upward movement of the knife 354 is adjustable in a manner similar to that previously explained, but in the modified apparatus, the roller 390 bearing on the wedge 370, is carried by a rod 392 threaded in a cross head 394 fastened to the push rod 382. The cross head and push rod are constantly urged downwardly so that the roller 384 engages the cam 302 by a spring 396 on a rod 398 passing through the cross head and fixed in a stationary bar 400. The bar is mounted on posts 402 fixedly mounted on the machine and preferably extending above the bar 402 to serve as guides for the cross head. The spring 396 thus holds the adjusting rod 392 so that its roller bears on the wedge 370 when the cross head is in its lowermost position and also holds the push rod roller on the cam. When the push rod is in its uppermost position, as indicated by the broken lines in Fig. 26, the adjusting roller 390 is lifted above the wedge member.

The edges of the cam 350 and 302 are so arranged that the movable parts of the modified apparatus will operate in time sequence to move the compressor block 318 to the dotted line position of Fig. 26, thereby to compress the filling material beneath the elevated knife 354 and simultaneously move the valve plate 338 until its port 340 is directly above the outlet 68; then to depress the ejector-knife while block 318 remains in its forwardmost position, thereby ejecting a filler biscuit through the outlet and into the shoe bottom cavity; then to depress the knife further to compress the filler material in the bottom cavity; and finally to elevate the knife to the full line position of Fig. 26.

A different, adjusted position of the ejector knife and its actuating and adjusting mechanism is illustrated in the fragmentary view of Fig. 27. In that view, the wedge 370 has been

moved to elevate the adjusting rod 392 and rocker arm 394, thereby moving the rocker arm 374 and the rod 362 to lower the position of the ejector-knife 354, so that the thickness of a filler biscuit is compressed beneath the knife in the position of Fig. 26. It will be observed that, in Fig. 27, the roller 384 at the bottom of the push rod 382 has been moved away from the cam 302; but that when the cam is rotated to the broken line position of the figure, it will then engage the roller 384 and elevate the push rod to depress the knife 354 and eject the filler biscuit. It will be understood that the upper limit of movement of the knife may be adjusted to intermediate position by varying the movement of the wedge 370 in the manner previously explained.

It is thus apparent that the modified machine shown in Figs. 26 and 27 functions in accordance with the basic principles of operation of the machine illustrated in Figs. 1 to 25, to achieve the desired result by substantially similar means. One machine or the other will work satisfactorily, whether the plastic filler is of a coarse or fine consistency. The coarse filler, composed of relatively large cork particles in a relatively dry plastic mass, should be compressed and formed into a biscuit in a machine of the type illustrated in Figs. 1 to 25, before the biscuit is ejected through the delivery outlet. The fine or dense filler, consisting of relatively small cork particles in a relatively moist and gummy plastic mass, need not be formed into a biscuit before its ejection but should be compressed in a machine, like that of Figs. 26 and 27, which has fewer moving parts in the filler chamber, so that the mechanism will not become clogged by the moist, gummy material.

We claim:

1. A shoe bottom filling machine comprising a chamber for receiving plastic bottom filling material, the chamber having side walls and a bottom provided with a delivery outlet, means for intermittently opening and closing said outlet, an ejector member movable downwardly and upwardly in said chamber toward and from said outlet to eject a biscuit of said material through the open outlet, means for successively elevating and depressing said ejector member with respect to the chamber bottom, a compressor member movable longitudinally between the sides of the chamber, and means for moving said compressor member to compress the material in said chamber beneath said ejector member while the latter is in elevated position.

2. A shoe bottom filling machine as described in claim 1, having manually adjustable means for limiting the extent of upward movement of the ejector member, whereby a filler biscuit of predetermined thickness is ejected through said outlet by downward movement of said ejector member after the material beneath it has been compressed.

3. A shoe bottom filling machine as described in claim 1, having a shoe support disposed beneath said chamber bottom and movable toward and from said outlet, and means for moving the support upwardly to press the bottom of a shoe supported thereon against said chamber bottom, whereby the biscuit ejected through said outlet is deposited in the shoe bottom cavity and will be compressed therein by continued downward movement of the ejector member.

4. A shoe bottom filling machine as described in claim 1, having a second compressor member movable longitudinally between said chamber

5
10
15

sides toward and from the first named compressor member, and means for moving the second compressor member to cooperate with the movement of the first compressor member in compressing said material beneath said elevated ejector member.

5. A shoe bottom filling machine as described in claim 1, in which a biscuit forming wall is disposed against the chamber bottom on one side of the outlet and the compressor member is movable toward the other side of said outlet and has a complementary biscuit-forming wall on its forward face, whereby the material compressed beneath said ejector member is preformed between said walls before its ejection through the outlet.

6. In a shoe bottom filling machine of the character described, a chamber containing plastic filling material, a delivery outlet in the bottom of said chamber, an ejector member movable upwardly to a position above said opening and reciprocable downwardly toward and through said opening, means in said chamber for forming a biscuit of compressed filling material immediately beneath said knife, manually adjustable means for regulating the extent of upward movement of said member, whereby the thickness of said biscuit may be predetermined, and means for depressing the knife to move the formed biscuit downwardly through said opening, whereby said biscuit may be deposited in the bottom cavity of a lasted shoe supported against the chamber beneath said opening and compressed in said cavity.

7. A shoe bottom filling machine comprising a chamber for receiving plastic bottom filling material, the chamber having side walls and a bottom provided with a delivery outlet, a ported valve plate slidable longitudinally of said chamber bottom for closing and opening said outlet, an ejector-knife movable downwardly and upwardly in said chamber toward and from said outlet, a compressor member at one end of said chamber, a second compressor member at the opposite end of said chamber, at least one of said members being slidable longitudinally of the chamber toward and from the other member, and power driven means for moving said valve plate, knife and movable compressor member, in timed relation, to compress the filling material in said chamber beneath said knife while the knife is elevated, and then to open said outlet and depress the knife to eject a biscuit of compressed bottom filler through the outlet and into the bottom cavity of a lasted shoe supported beneath said outlet.

8. A shoe bottom filling machine as described in claim 7, having manually adjustable means for limiting the extent of upward movement of the ejector-knife whereby a filler biscuit of predetermined thickness is ejected by said knife.

9. A shoe bottom filling machine as described in claim 7, having means operatively connected to said power driven means for supporting a shoe beneath said outlet and pressing the shoe bottom toward the chamber bottom at said outlet while the knife is ejecting said biscuit through said outlet.

10. A shoe bottom filling machine as described in claim 7, both said compressor members being slidable longitudinally of the chamber and said power driven means including means for moving both members, the forward face of at least one of said members having a biscuit-forming wall and the chamber bottom having a complementary biscuit forming wall, said ejector-knife being sup-

75

ported on one of said members, whereby compressive movement of said members performs a filler biscuit between said walls and beneath said knife.

11. A shoe bottom filling machine comprising a chamber for receiving plastic bottom filler material, the chamber having side walls and a bottom provided with a delivery outlet, a ported valve plate slideable longitudinally of said chamber bottom for opening and closing said outlet, an ejector member movable downwardly and upwardly in said chamber toward and from said outlet, a transverse wall extending across the chamber at one side of said outlet, a compressor member fixed to said plate and movable therewith between the side walls of the chamber toward and from the opposite side of said outlet, means for moving the valve plate and compressor member to compress the filler material beneath said ejector member and between said member and said transverse wall while the port of the valve plate is moved into registration with said outlet, and means for moving the ejector member downwardly toward and through said outlet to eject a filler biscuit therethrough.

12. A shoe bottom filling machine as described in claim 11, having manually adjustable means for limiting the extent of upward movement of the ejector member, whereby the thickness of the biscuit ejected thereby may be predetermined.

13. A shoe bottom filling machine comprising a casing adapted to receive movable blocks within its opposite ends and to receive plastic filling material within a chamber in its central portion, the casing having a base provided with delivery opening disposed beneath said chamber, a compressor block slideable longitudinally in one end of said casing, a second compressor block slideable longitudinally in the opposite end of said casing, the forward end of one of said blocks carrying a vertically movable slide guide having an ejector knife at its lower end, said knife being movable downwardly toward and through said opening when positioned thereover, and upwardly into said chamber, said blocks having opposed forward ends movable into said chamber to compress the plastic material therein between said ends and beneath said knife, a ported valve plate slideable in the bottom of the casing above said opening, and power-driven means for moving said blocks, said ejector-knife and said valve plate, in timed relation, to compress the filling material beneath said knife and above said opening and to eject a biscuit of compressed filling material through the valve port and through said opening onto the bottom of a lasted shoe supported beneath said opening.

14. A shoe bottom filling machine comprising a casing adapted to receive movable blocks within its opposite ends and to receive plastic filling material with a chamber in its central portion, the casing having a base provided with delivery opening disposed beneath said chamber, a compressor block slideable longitudinally in one end of said casing, a second compressor block slideable longitudinally in the opposite end of said casing, the forward end of one of said blocks carrying a vertically movable slide having an ejector-knife at its lower end, said knife being movable downwardly toward and through said opening when positioned thereover, and upwardly into said chamber, said blocks having opposed forward ends movable into said chamber to compress the plastic material therein between said ends and beneath said knife, a ported valve plate slideable in the bottom of the casing above said

opening, manually adjustable means for limiting upward movement of the ejector-knife, and power-driven means for moving said blocks toward each other to position said knife above said opening and compress the material beneath said knife, for moving said valve plate to bring its port over said opening, and for depressing the knife through said port and opening to eject a filler biscuit of predetermined thickness onto the bottom of a lasted shoe supported beneath said opening.

15. A shoe bottom filling machine comprising a casing adapted to receive movable blocks within its opposite ends and to receive plastic filling material with a chamber in its central portion, the casing having a base provided with delivery opening disposed beneath said chamber, a compressor block slideable longitudinally in one end of said casing, a second compressor block slideable longitudinally in the opposite end of said casing, the forward end of one of said blocks carrying a vertically movable slide having an ejector-knife at its lower end, said knife being movable downwardly toward and through said opening when positioned thereover, and upwardly into said chamber, said blocks having opposed forward ends movable into said chamber to compress the plastic material therein between said ends and beneath said knife, a ported valve plate slideable in the bottom of the casing above said opening, a shoe support disposed below said opening and movable upwardly toward said base, whereby the forepart bottom of a lasted shoe placed on said support may be moved against said base to receive filling material ejected through said opening, and power-driven means for actuating, in timed relation, said blocks, ejector-knife, valve plate and shoe support, to compress the filling material beneath said knife and above said opening, then to bring the port of the valve plate over said opening and depress the ejector-knife to eject a filler biscuit through said port and opening, and then to elevate the shoe support and further depress the knife to compress and spread the biscuit in the cavity of the shoe bottom.

16. A shoe bottom filling machine comprising a casing adapted to receive movable blocks within its opposite ends and to receive plastic filling material with a chamber in its central portion, the casing having a base provided with delivery openings disposed beneath said chamber, a compressor block slideable longitudinally in one end of said casing, a second compressor block slideable longitudinally in the opposite end of said casing, the forward end of one of said blocks carrying a vertically movable slide having an ejector-knife at its lower end, said knife being movable downwardly toward and through said opening when positioned thereover, and upwardly into said chamber, said blocks having opposed forward ends movable into said chamber to compress the plastic material therein between said ends and beneath said knife, a ported valve plate slideable in the bottom of the casing above said opening, a shoe support disposed below said opening and movable upwardly toward said base, whereby the forepart bottom of a lasted shoe placed on said support may be moved against said base to receive filling material ejected through said opening, and power-driven means for actuating, in timed relation, said blocks, ejector-knife, valve plate and shoe support, to compress the filling material beneath said knife and above said opening, then to bring the port of the valve plate over

said opening and depress the ejector-knife to eject a filler biscuit through said port and opening, and then to elevate the shoe support and further depress the knife to compress and spread the biscuit in the cavity of the shoe bottom, and manually adjustable means for regulating the extent of upward movement of the ejector-knife, whereby the thickness of the ejected biscuit may be predetermined.

17. A shoe bottom filling machine comprising an elongate casing adapted to receive movable blocks within its opposite ends and to receive plastic filling material within a chamber in its central portion, the casing having substantially parallel, longitudinal sides and a base having a delivery opening therethrough beneath said chamber, a biscuit-forming wall extending across the bottom of said chamber directly above one side of said opening and substantially corresponding in contour to a substantial portion of the periphery of said opening, a compressor block 10 slideable in one end of said casing toward and from said chamber, a second compressor block slideable in the opposite end of the casing toward and from said wall and having a forward surface substantially corresponding in contour to the remaining portion of the periphery of said opening, said wall and surface constituting biscuit forming members, an ejector-knife having a guide mounted for vertical sliding movement on the forward end of said second block, said knife having a periphery substantially corresponding to the periphery of said opening and being movable downwardly through said opening when positioned thereover, and upwardly above said wall, a valve plate slideable longitudinally of the casing base above said opening and having a port therethrough adapted to be moved into substantial registration therewith, and power-driven means for moving said blocks, said ejector-knife and said valve plate in timed relation, to form a biscuit of compressed filling material between said wall and said surface and beneath said ejector-knife, and to eject the biscuit through said port and opening onto the bottom of a lasted shoe supported beneath said opening.

18. A shoe bottom filling machine comprising an elongate casing adapted to receive movable blocks within its opposite ends and to receive plastic filling material within a chamber in its central portion, the casing having substantially parallel, longitudinal sides and a base having a delivery opening therethrough beneath said chamber, a biscuit-forming wall extending across the bottom of said chamber directly above one side of said opening and substantially corresponding in contour to a substantial portion of the periphery of said opening, a compressor block slideable in one end of said casing toward and from said chamber, a second compressor block slideable in the opposite end of the casing toward and from said wall and having a forward surface substantially corresponding in contour to the remaining portion of the periphery of said opening, said wall and surface constituting biscuit forming members, an ejector-knife having a guide mounted for vertical sliding movement on the forward end of said second block, said knife having a periphery substantially corresponding to the periphery of said opening and being movable downwardly through said opening when positioned thereover, and upwardly above said wall, a valve plate slideable longitudinally of the casing base above said opening and having a port therethrough adapted to be moved into substantial

registration therewith, a shoe support disposed below said opening and movable upwardly toward said base, whereby the forepart bottom of a lasted shoe placed on said support may be moved against said base to receive a biscuit of filling material ejected through said opening, and power driven means for actuating, in timed relation, said blocks, ejector-knife and shoe support, to form a biscuit of compressed filling material between said wall and said surface, and immediately beneath said knife and above said opening, then to bring the port of the valve plate into registration with said opening, and depress the knife to eject the biscuit through said port and opening into the cavity of the forepart bottom and then to elevate the shoe support to press said bottom against said base and simultaneously further depress the knife to compress and spread the biscuit in said cavity.

19. A shoe bottom filling machine comprising an elongate casing adapted to receive movable blocks within its opposite ends and to receive plastic filling material within a chamber in its central portion, the casing having substantially parallel, longitudinal sides and a base having a delivery opening therethrough beneath said chamber, a biscuit-forming wall extending across the bottom of said chamber directly above one side of said opening and substantially corresponding in contour to a substantial portion of the periphery of said opening, a compressor block slideable in one end of said casing toward and from said chamber, a second compressor block slideable in the opposite end of the casing toward and from said wall and having a forward surface substantially corresponding in contour to the remaining portion of the periphery of said opening, said wall and surface constituting biscuit-forming members, an ejector-knife having a guide mounted for vertical sliding movement on the forward end of said second block said knife having a periphery substantially corresponding to the periphery of said opening, and being movable downwardly through said opening when positioned thereover, and upwardly above said wall, a valve plate slideable longitudinally of the casing base above said opening and having a port therethrough adapted to be moved into substantial registration therewith, a shoe support disposed below said opening and movable upwardly toward said base, whereby the forepart bottom of a lasted shoe placed on said support may be moved against said base to receive a biscuit of filling material ejected through said opening, and power-driven means for actuating, in timed relation, said blocks, ejector-knife and shoe support, to form a biscuit of compressed filling material between said wall and said surface, and immediately beneath said knife and above said opening, then to bring the port of the valve plate into registration with said opening, and depress the knife to eject the biscuit through said port and opening into the cavity of the forepart bottom, and then to elevate the shoe support to press said bottom against said base, and simultaneously further depress the knife to compress and spread the biscuit in said cavity, and manually adjustable devices associated with the means for actuating the ejector-knife for regulating the extent of upward movement of said knife, whereby the thickness of the biscuit may be predetermined by adjusting said devices before the machine is operated.
